UNITED STATES PATENT OFFICE

2,307,678

COLLAPSIBLE WALL FORM

Hal Hayes, Los Angeles, Calif.

Application November 26, 1938, Serial No. 242,506

8 Claims. (Cl. 25—131)

This invention relates to building construction and particularly pertains to collapsible wall forms.

Heretofore, buildings have been made of concrete in which temporary moulds have been built to receive poured concrete and which segmental pre-formed moulds have been built to be erected and dismantled or moved in units. Such structures have been shown in my patent entitled "Concrete forms" issued by the United States Patent Office September 29, 1936, and bearing the Number 2,055,977. These structures necessitate the separate erection of a plurality of wall sections which are assembled as erected to form a wall of predetermined area and must thereafter be separately removed. In connection with these sections it is necessary to provide means to properly align the sections with relation to each other so that the corners of the walls will be square and so that the wall surfaces will be plumb. It has been found desirable to design a concrete form in which all of the wall sections are permanently assembled with relation to each other so that the form for a complete room or building section may be manufactured and thereafter set in place, and it is the principal object of the present invention to provide a building form structure having elements which may be moved as a unit to delineate and form the walls of a room or series of rooms and which will cooperate with other form elements to provide form spaces into which cementitious material may be poured, the invention having the further object in view of providing cooperating members to form wall openings and in constructing the forms so that they may be withdrawn from contact with the cast wall surfaces and thereafter withdrawn from position within the cast structure by simple and direct acting means.

The present invention contemplates the provision of a form structure which is collapsible in arrangement and which collapsible structure cooperates with other form elements to provide a hollow wall for a room of any given dimension and to cast wall openings therein as required.

The invention is illustrated by way of example in the accompanying drawings, in which:

Figure 1 is a view in transverse vertical section through a wall formed with the present apparatus and indicates the positions of the inside and outside forms with which the present invention is concerned.

Fig. 2 is a fragmentary view in vertical transverse section showing another form of footing construction than that disclosed in Fig. 1.

Fig. 3 is a view in transverse section as seen on the line 3—3 of Fig. 2 showing a floor or ceiling construction.

Fig. 4 is a fragmentary view similar to that disclosed in Fig. 3 showing a form of footing and anchor for the form elements.

Fig. 5 is a view in plan showing the construction of the inside room form.

Fig. 6 is a view in vertical section and elevation 10 through the inside form as seen on the line 6—6 of Fig. 5.

Fig. 7 is a fragmentary view in elevation as viewed in the direction of the arrow 7 in Fig. 5 and discloses the adjusting and aligning means 15 of the form.

Fig. 8 is a fragmentary view in vertical section and elevation showing a wall footing construction.

Fig. 9 is a fragmentary view in vertical section 20 showing a temporary positioning means for wall forms.

Fig. 10 is a view similar to Fig. 9 showing another form of wall forming positioning means.

Fig. 11 is a view in plan showing an inside wall 25 form in which wall slabs are hinged together.

Fig. 12 is a view in elevation showing this particular form as collapsed.

Fig. 13 is a fragmentary view of a wall showing 30 means provided for casting a wall opening in a wall section.

Fig. 14 is a view in transverse section as seen on the line 14—14 of Fig. 13, showing the construction of the frame and wall opening.

Fig. 15 is a fragmentary view in perspective 35 showing the means of locking wall form elements together along their contiguous edges.

Fig. 16 is a fragmentary view in plan showing the manner in which the corners of wall form elements are secured together.

Fig. 17 is a view drawn at a reduced scale showing 40 the construction of one of the outer wall form elements.

Fig. 18 is a fragmentary view in perspective showing an expanding unit for increasing the 45 length of a form and the manner in which it is locked.

Fig. 19 is an enlarged fragmentary view in perspective showing the form locking and centering means along contiguous edges.

Fig. 20 is a view in perspective showing the upper portion of the form structure as assembled 50 as indicated in Fig. 1 but more particularly disclosing the manner in which a filling hopper is placed in position.

Referring more particularly to the drawings,

10 indicates a concrete footing. This footing delineates the outline of the rooms of a dwelling and provides a foundation therefor. In the form of the footing, as shown in Fig. 1, it is constructed with a relatively wide portion seated within a trench in the ground and an upper relatively narrow portion projecting above the ground. This upper portion has a horizontal face 11 and side faces 12. The footing, as will be understood, is preferably made of cementitious material. Disposed at opposite sides of the upwardly projecting portion of the footing and lying against the faces 12 are supporting rails 13 and 14. These rails may be secured in position in any desired manner. The rail 13 may support a floor slab 15, the upper face of which lies in the same horizontal plane as the face 11 of the footing.

Extending across the face 11 and over the upper face of the floor slab, as shown in Fig. 1, are spacing bars 16 which may be held in position in any suitable manner such as for example by driving a nail 17 through an opening therein and then driving the nail into the rail 14. The spacing bars 16 are formed with angle elements 18 at their outer sides with relation to which outer wall forms 19 are held against spreading action and with their plane surfaces in vertical alignment with the face 12 of the footing.

Detachably mounted on the upper face of the inner ends of the spacing bar 16 are channel members 20. These members are secured in position upon the bars by cap screws 21. The outermost leg of these channel members stands vertically and abuts against the back face of inner wall forms 22. Locking pins 23 extend horizontally from the outer legs of the channels 20 and interlock with the form 22 to be held against movement. The opposite legs of the channel elements 20 are engaged by a spacing bar 24.

Detachably secured to the outer extending ends of the bars 16 are diagonal bracing members 25 which are fitted with jaws 26 and a set screw 27 for clamping them in position where required. The upper ends of these members are secured by elements 28 to the frame structure 19. The frame structure 19 is formed with a continuous smooth surfaced plate 29 which represents the area to be moulded. As here shown, this plate is of a height equal to the height of the wall to be cast. It is bounded around its edges by reinforcing angles 30, and as shown in Fig. 17 of the drawings may be vertically and horizontally reinforced by structural members 31 and 32. Suitable vertically extending trusses 33 are provided and where required horizontally extending trusses 34 are used. This insures that although the plate 29 is of relatively thin gauge that it will be reinforced to withstand considerable pressure uniformly exerted by the mass of concrete being cast into the wall. This general type of form was shown in United States Letters Patent No. 2,055,977 issued to me on September 29, 1936.

Resting upon the spacing bars 16 are removable core structures 35 which are preferably of the type shown in my co-pending application entitled "Collapsible core," Serial No. 169,098, filed by me on October 15, 1937. This type of core is characterized by the fact that its side walls 36 are articulately connected to each other and may be held in their expanded positions by suitable expanding means 37 and 38 which bear against reinforcing ribs 39. The upper end of the core is held in its expanded position and in its spaced

relation to the form elements 19 and 22 by spacing bars 40, which carry lugs 41 and 42 extending downwardly into the mouth of the core and between the walls 36. The lug 42 is mounted upon a swinging lever 42'. The member 40 carries a cover plate 43 which closes the space between the plate 29 and the wall plate 36.

After the forms have been set a hopper structure is placed over the open top of the forms as shown in Fig. 20. This structure includes cross members 40 and a lever 40' having a catch 44 which fits beneath the upper angle element 30 of the frame 19 and holds the bar down and in position. An angle hook 44' is carried at the opposite end of the bar 40 and when disposed beneath the flange of a frame element 54 will co-operate with the lever 40' in holding the bar 40 in place. Carried by one or more of the spacing bars 40 is a hopper 45 by which concrete may be filled into the spaces 46 and 47 occurring around the cores 35 and between the form elements 19 and 22. Thus, it is possible to quickly fill these spaces while holding the various form elements in proper assembled and spaced relation to each other.

A feature of particular importance in the present case is the construction of the inside forms, generally indicated at 22 and shown in particular in Figs. 5 and 6 of the drawings. These forms define the inside wall of a room. Heretofore, at least four forms have been required to delineate the inside wall surface. With the present invention one form unit is provided, around which the outside forms 19 are arranged and which inside form unit may be set in position as a unit and removed therefrom in the same manner as removing a collapsible core 35 in a wall section. The inside form 22 comprises side wall sections 49, 50, 51 and 52, as here shown, for producing a room space of rectangular shape. It is to be understood that the dimensions of the various walls might be changed or that other room configurations might be made without departing from the spirit of the invention.

As shown in Fig. 5, the various wall sections 49 to 52, inclusive, are each constructed from continuous sheet plates 53 which are bent at the corners and which are reinforced by horizontal angle members 54 and vertical trusses 55. The sheet plates 53 bent around the corners abut against each other along vertical lines as at 53'. These edges are reinforced by the angle members 32. The angles are held together as shown in Fig. 19 and in a manner to be herein-after explained.

Attention is directed to the fact that the horizontal angle members 54 are of a length shorter than that represented by the wall form upon which they are applied so that spaces 56 may occur at the corners of the form 22, thereby allowing a limited amount of articulate action between the various form sections at the corners so that the entire form structure 22 may be contracted sufficiently after a form has been made to draw it out of contact with the moulded surface and to permit it to be lifted from the enclosure without frictional engagement between the surfaces of the member 53 and the wall which has been cast.

The form structure 22 is braced between opposing walls by collapsible bracing elements 57 and is braced diagonally from points adjacent the corners of the form by adjustable braces 58. The collapsible braces 57 are hinged at 59 to

vertical truss members 55 of the form and are hinged also at 60 to a vertical draw-bar 61. This draw-bar extends to a point above the top of the form structure 22 and is provided with an eye 62 in which a hoisting hook may be placed.

The cross brace members 57 when pulled inwardly, as their upper pivoted ends are pulled upwardly by the member 61, will tend to deflect the plate 53 between its corners and will pull the plate away from the surface of the moulded mass of cementitious material so that thereafter the form may be elevated from the confined area produced by the moulded wall. This flexure extends entirely to the corners which may flex also to accommodate the action. In order to hold the wall structure against flexure while the concrete is being poured the brace members 57 may be moved to a horizontally aligned position, as shown in Fig. 6 of the drawings. This action will be supplemented by the action of the diagonal members 58 which comprise a horizontal compression element 63 resting upon the end of a compression element 64. The element 63, as particularly shown in Fig. 7 of the drawings, is formed with a flange 65 through which a bolt 66 is threaded. This bolt bears against a stop member 67 rigidly secured to the compression member 64 so that pressure may be exerted to hold the compression members 63 and 64 in a rigid distended position between their points of contact with the wall form sections. A lock nut 68 is provided on each of the bolts. Rigid horizontal members 57 are carried by the post 62 and their outer ends serve as stops against which members 55 may move when the form is being collapsed.

In the form of the invention shown in Figs. 11 and 12 the inside form structure 22 is shown as being collapsible so that it may be more readily transported from place to place. In this particular device the side wall sections 49, 50, 51 and 52 are each made with a permanent corner 69 adjacent to which is a vertical hinge 70. The vertical hinge 70 thus does not occur in the corner but adjacent thereto, thus insuring that the corner which is moulded will not be irregular or broken, and at the same time insuring that the frame may be collapsed and readily withdrawn from position within the moulded structure.

It may be found desirable to vary the construction of the footing 10 and to temporarily anchor the form elements by different arrangements. Such variations are shown in Figs. 2, 4, 8, 9 and 10. In Fig. 2 it will be seen that the footing 10 is formed with a shoulder 71, upon which a floor joist 72 may rest. This beam is indicated in Fig. 3 as being cast of cementitious material and tied to the floor slab 15 by suitable reinforcing and tie means 73. The wooden members 13 and 14 are varied accordingly and are here shown as secured together by tie bolts 74 which extend through the mass of concrete and carry plates 75 and 76 to hold the form sections 19 and 22 in position.

In the form of the invention shown in Fig. 4 the construction of Fig. 2 is varied slightly and the floor slab is supported upon a transverse beam 13. Separate fastening and seat members 77 and 78 are provided which receive the lower edges of the frame structures 19 and 22 and are bolted together by the bolts 74.

In the form of the invention shown in Fig. 8 side beams 13 and 14 carry angle members 79 and 80 which are secured in place by bolts 74. The angle members thus present a horizontal face upon which the form sections 19 and 22 may

rest. Angle bars 81 and 82 are carried on the angle members and limit outward movement of the form elements during the moulding operation.

Figs. 9 and 10 show structures in which the 5 form elements are set up on a floor. In Fig. 9 the floor slab 15 is shown as being formed with channels 83 and 84 in which the form elements 19 and 22 may be positioned. In Fig. 10 lock screws 85 having T-heads are positioned in the floor to limit 10 outward movement of the form structures 19 and 22 and to hold the lower edges of the form structures against the floor during the moulding operation.

As previously explained, it is desirable to provide 15 form means by which door and window openings may be cast by the use of the moulds here disclosed. This is accomplished by providing a metal window frame 86 which may be set in a position and filled with concrete permanently 20 so that when the forms 19 and 22 are removed the window frame will be a permanent part of the wall. The window frame structure is held in position by a frame 87 which fits within the opening of the window frame. Bolting plates 88 are 25 provided and may receive bolts 89 extending through openings in the plates of the form structures 19 and 22 to properly support and position the frame. The frame 87 is indicated as being of angle sectioned material and carries a plurality of 30 saddle members 90. These members, as shown in Fig. 14 of the drawings, extend over the face of the inner perimeter of the window frame 86 to position the same. The saddles are suitably secured to the frame structure 87 by cap screws 91. 35 Plates 92 are secured to the frame structure for the purpose of withdrawing the supporting frame 87 after the wall frames 19 and 22 have been removed. It will thus be seen that by this arrangement it is not necessary to cut wall openings 40 after the concrete has been set, for these openings are cast utilizing the permanent window frame as the mould therefor.

In some instances it may be necessary to connect 45 a plurality of frame sections 19 along their vertical edges. A suitable arrangement is shown in Fig. 15 of the drawings where the contiguous vertical flanges 30 carry overlapping structural elements 93 and 94 which when assembled, as shown in Fig. 15, will receive a pin 95 to hold them together. The upper edges of the frame structures may be held together by a channel plate 96 which has overlapping flanges 97 extending downwardly along opposite faces of the forms.

In order to secure the forms together at the 55 corners an angle member 98 is provided, as shown in Fig. 16 of the drawings. This member is formed with openings to receive pins 99 which fit into the corner between the angles 30 of the frame structures.

In operation of the present invention a foot- 60 ing or base structure may be made as required. It has been found in practice that it is only necessary to provide a relatively shallow foundation trench which delineates the floor plan of the building, after which the footings 10 are cast to form the foundation. These footings may be as desired, such for example as shown in Figs. 1, 2, 4 and 8. When a floor has already been laid 65 the form elements may be erected on the floor and in the case of concrete flooring means for positioning the forms may be utilized as shown in the Figs. 9 and 10. In any event the inside form 22 is set in position with its transverse brace members 57 disposed horizontally as shown

in Fig. 6 of the drawings and with the diagonal bracing 58 set by the adjusting screws 66 to hold the structure rigid. This internal frame may be locked and held by any of the means shown in Figs. 1, 2, 4 and 8 and will thus retain its position when the force of poured concrete is exerted against it.

In the form of the invention shown in Fig. 1 a lower cross brace 24 is provided to extend from one side wall of the room to the other and to hold the positioning means 20 in place. It may also be found desirable to brace the form at intervals throughout its height and space the core structures 35 with means such as the transverse brace rod 100 shown in Fig. 1 of the drawings. Here it will be seen that this brace rod extends into a sleeve 101 and may project through an opening in the plate 53 of the form 22 to be imbedded temporarily in the concrete, as indicated by dotted lines. After the concrete has been poured it may be withdrawn to the position indicated in solid lines and the pin 102 inserted through another opening in the member 100 to hold it in place and prevent leakage of concrete. The outer form elements may then be erected with reference to the positioning member 18, as shown in Fig. 1 of the drawings. If the outer forms require more than one form section the contiguous vertical edges may be fastened together, as shown in Fig. 15, and at the corners the edges of the 30 form sections may be fastened together as shown in Fig. 16. The cores 35 may then be lowered into position, after which the bars 40 are disposed over the top of the cores so that their spacing lugs 43 will extend between the form walls 29 and 53 and the core walls 36. The bars 40 may then be secured in position, as shown in Fig. 1 of the drawings.

As previously explained, a hopper 45 is carried by certain of the bars 40 so that concrete may be easily poured into the hopper and directed into the spaces 46 and 47 occurring at opposite sides of the core. In the event that wall openings are required, the frames 86 for such openings may be secured in position by the holding frames 87. The 45 concrete may then be poured.

After the concrete is set the forms 19 and 22 may be removed. The inner form 22 is removed by releasing the compression of the adjusting bolt 66 on the diagonal member 58 and removing braces such as indicated at 24 and 100. The vertical bar 61 may then be grasped and pulled upwardly. This will pull the outer ends of the transverse brace members 57 inwardly and will flex the plate 53 between the corners, after which further upward movement will cause the entire form structure to be lifted from position. The outer frame elements 19 may then be taken down. It is to be understood that the wall opening frames 87 will have been detached from the form structure 19 or 22 to which it had been secured so that it will remain in place until after the side forms have been taken down. The saddle members 90 will then be detached from the frame structure 87 so that the frame structure and the saddle members can be removed from the position shown in Fig. 14.

In the form of the invention shown in Fig. 5 it has been described that the plates 53 are bent around the corners of the form so that they will flex and so that the edges of the plates meet as is shown at 53'. These meeting edges are reinforced by the vertical angle elements 30, which elements include means for readily aligning the plates with relation to each other and means for locking the

5 plates. Such means are shown in Figs. 18 and 19 of the drawings, where it will be seen that the angle member 30 of one plate 53 carries a series of aligning pins 110 which are preferably square or rectangular in section and project into corresponding openings 111 in the parallel flange of a contiguous angle member. Also carried by the flange of an angle member 30 is a plurality of lock pins 112 which project through openings 113 in the adjacent flange of a contiguous angle plate. The projecting portion of the pins 113 are formed with vertically extending slots 114 which receive wedge members 115. These wedge members may be driven down into position and will tightly draw the adjacent flanges of the contiguous angles 30 against each other.

It is to be understood that due to variation in the lineal dimensions of rooms it may be desirable to increase the length of a side of a room over the length created by the plates 53. This is accomplished by providing intermediate members 116 which are in the shape of wall form slabs and which may fit between the contiguous edges 53' of the wall forms. These slabs may be of any desired width and are provided with the interlocking and holding means shown in Figs. 18 and 19. It will thus be seen that due to this particular arrangement it is possible to quickly assemble a form unit which will take care of a wall, defining the perimeter of a room of any desired dimensions.

It will thus be seen that by the construction here disclosed a complete building including any desired number of rooms and any desired room arrangement may be quickly built in a monolithic structure, which insures that a building of suitable strength may be constructed at a relatively small cost both as to material and labor.

While I have shown the preferred form of my invention and method of using the same, it will be understood that various changes may be made in combination, construction and arrangement of parts by those skilled in the art, without departing from the spirit of my invention as claimed.

Having thus described my invention, what I claim and desire to secure by Letters Patent is:

1. In combination, an outer form element resting upon a foundation footing, means holding said outer form element against relative movement with relation to said footing, an inner collapsible form unit resting upon said footing and including all wall sections corresponding to the wall of an enclosure to be formed, means holding said inner form element against lateral movement relative to the footing and the first form element, means at the upper edges of said form elements for spacing and holding said elements with their opposing faces in spaced parallel relation to each other, an intermediate core element resting upon the footing and positioned between said form members, and means extending through the wall of a form member for temporarily holding the intermediate core in a fixed position while cementitious material is being poured around it, after which said intermediate core may be collapsed and retracted from the mass of material forming the wall.

2. In combination with an outer wall form defining the vertical outer face of a wall of an enclosure such as a room, an inner wall form spaced from the outer wall form with vertical faces parallel to the faces of the outer wall form, said inner wall form being characterized as comprising a continuous form unit including inner wall form sections for each of the wall surfaces

to be formed, said sections having limited flexibility between wall corners, means associated with said wall form sections whereby force may be exerted against said sections to cause the same to flex, means connected with said force exerting means for lifting the entire wall form structure bodily from the enclosure, and means for limiting the flexing movement of the wall form sections.

3. In combination with an outer wall form defining the vertical outer face of a wall of an enclosure such as a room, an inner wall form spaced from the outer wall form with vertical faces parallel to the faces of the outer wall form, said inner wall form being characterized as comprising a continuous form unit including inner wall form sections for each of the wall surfaces to be formed, said sections having limited flexibility between wall corners, means associated with said wall form sections whereby force may be exerted against said sections to cause the same to flex, means connected with said force exerting means for lifting the entire wall form structure bodily from the enclosure, and separate means for positively and temporarily holding said wall form sections against flexure.

4. In combination with an outer wall form defining the vertical outer face of a wall of an enclosure such as a room, an inner wall form spaced from the outer wall form with vertical faces parallel to the faces of the outer wall form, said inner wall form being characterized as comprising a continuous form unit including inner wall form sections for each of the wall surfaces to be formed, said sections having limited flexibility between wall corners, means associated with said wall form sections whereby force may be exerted against said sections to cause the same to flex, means connected with said force exerting means for lifting the entire wall form structure bodily from the enclosure, and separate means for positively and adjustably holding said wall form sections against flexure.

5. In combination with an outer wall form structure adapted to define the outer vertical surfaces of a wall forming an enclosure such as a room or the like, an inner form structure comprising panels defining the inner wall faces of the enclosure, said panels including sections articulately associated at their corners and capable of limited flexibility throughout the horizontal length of the wall sections, separate means connected with said panels intermediate their ends and extending diagonally of the inner form structure whereby the panels will be positively locked against flexure and whereby movement of said means to unlocked positions will flex the panels and contract the form, and lifting means associated therewith to lift the form thus contracted.

6. In combination with an outer wall form structure adapted to define the outer vertical surfaces of a wall forming an enclosure such as

a room or the like, an inner form structure comprising panels defining the inner wall faces of the enclosure, said panels including sections articulately associated at their corners and capable of limited flexibility throughout the horizontal length of the wall sections, separate means connected with said panels intermediate their ends and extending diagonally of the inner form structure whereby the panels will be positively locked against flexure and whereby movement of said means to unlocked positions will flex the panels and contract the form, lifting means associated therewith to lift the form thus contracted, and diagonal brace members adjustably positioned within the form structure at points adjacent to the corners thereof whereby the form will be held against collapse when cementitious material is being poured around it.

7. In combination with an outer wall form structure adapted to define the outer vertical surfaces of a wall forming an enclosure such as a room or the like, an inner form structure comprising panels defining the inner wall faces of the enclosure, said panels including sections articulately associated at their corners and capable of limited flexibility throughout the horizontal length of the wall sections, separate means connected with said panels intermediate their ends and extending diagonally of the inner form structure whereby the panels will be positively locked against flexure and whereby movement of said means to unlocked positions will flex the panels and contract the form, form splicing slabs adapted to be interposed between contiguous vertical edges of the panel members, and means for locking said slabs in position.

8. In combination an outer wall form structure adapted to define the outer vertical surface of a wall forming an enclosure such as a room or the like, an inner form structure comprising panels defining the inner wall faces of the enclosure, said form structures being in spaced relation to one another between which cementitious material may be poured, collapsible means carried by said form elements and bridging the space therebetween to block out a desired area between the forms whereby when the wall is cast a wall opening will be formed completely therethrough, said inner form structure comprising panels defining the inner wall faces of the enclosure, said panels including sections articulately associated at their corners and capable of limited flexibility throughout the horizontal length of the wall sections, means connected with said panels intermediate their ends whereby the panels will be positively locked against flexure and whereby movement of said means to unlocked positions will flex the panels and contract the form, and lifting means associated with the panels to contract and lift the form.

HAL HAYES.
